DRAINER FOR DISHES, GLASSWARE, AND SILVERWARE

Henry J. Watral, Ramsey, N. J.

Application July 18, 1950, Serial No. 11,245

Term of patent 14 years

(Cl. D44—29)

To all whom it may concern:

Be it known that I, Henry J. Watral, a citizen of the United States, residing at Ramsey, in the county of Bergen and State of New Jersey, have invented a new, original, and ornamental Design for a Drainer for Dishes, Glassware, and Silverware, of which the following is a specification, reference being had to the accompanying drawings, forming a part thereof.

In the drawings:

Fig. 1 is a perspective view of a drainer for dishes, glassware, and silverware, showing my new design;

Fig. 2 shows a longitudinal section taken on the line 2—2 of Fig. 1, while

Fig. 3 is a fragmentary sectional view on the line 3—3 of Fig. 1.

The dominant feature of the instant design resides in an open wirework type of dish drainer of substantially rectangular configuration symmetrical about a transverse centrally located plane forming two similar half portions; each half portion having a bottom wire section, adjacent an outer end thereof, characterized by two contiguous rows of open wirework squares extending from side to side of the drainer, and a row of spaced, inwardly projecting pointed loop members extending from side to side of the drainer, said row of loop members being located intermediate the rows of open wirework squares and the inner end of the half portion all as shown.

I claim:

The ornamental design for a drainer for dishes, glassware, and silverware, as shown and described.

HENRY J. WATRAL.
